UNITED STATES PATENT OFFICE.

FRANCIS O. HELTZEL, OF WARREN, OHIO.

CONCRETE FORM.

Application filed March 15, 1922. Serial No. 543,868.

To all whom it may concern:

Be it known that I, FRANCIS O. HELTZEL, a citizen of United States, residing at Warren, in the county of Trumbull and State of Ohio, have invented certain new and useful Improvements in Concrete Forms, of which the following is a specification, reference being had therein to the accompanying drawing.

10 The present invention relates to concrete forms, and more particularly to road forms using rails for defining the edges of a concrete road, sidewalk, or the like.

One of the objects of the invention is the 15 provision of a novel stake receiving member carried by the rail.

Another object is the provision of a novel and improved device for holding in place the adjacent ends of the rails and clamping them together in abutment, whereby to maintain such rails in alinement and to support the ends thereof against depression under the weight of a road finishing machine or other apparatus run on the rails.

25 Another object is to provide such a device for obtaining a secure and rigid joint between the rail ends, whereby to prevent the separation of the rails, as well as the lateral or vertical displacement thereof, and which 30 will enable the rails to be conveniently moved laterally into and out of position when disconnected.

A further object is the provision of such 35 a rail joint which utilizes a stake as a part thereof, for securing the rails together, and to also hold the rail ends in place on the ground when the stake is driven down into place.

A still further object is the provision of 40 such a rail joint including a slip joint connection between the rail ends of such a kind that the rails can be assembled and separated by a lateral movement thereof, and means being provided for clamping the rail sections together when assembled.

It is also an object of the invention to provide such a concrete form construction which is comparatively simple and inexpensive, as well as being convenient, practical and efficient in use.

With the foregoing and other objects in view, which will be understood as the description proceeds, the invention resides in the construction and arrangement of parts, 55 as hereinafter described and claimed, it being understood that changes can be made

within the scope of what is claimed, without departing from the spirit of the invention.

The invention is illustrated in the accompanying drawings, wherein—

Figure 1 is a side elevation showing the joints between three rails and an intermediate stake socket member, portions of the intermediate rail being broken away.

Fig. 2 is a perspective view of a complete rail.

Fig. 3 is a vertical cross section on the line 3—3 of Fig. 1.

Fig. 4 is a longitudinal section on the line 4—4 of Fig. 1.

Fig. 5 is a view similar to Fig. 1 showing a supplementary set of rails mounted on the main rails.

The rails 10, such as are used in the construction of concrete roads, and the like, as shown, are of sheet metal or rolled stock having the upright portions or webs 11, with outturned base flanges 12 at their lower edges and the outturned top or tread flanges 13 at their upper edges. These rails are laid end to end and the road is built up by pouring the concrete between the opposite rails, which serve to define the edges of the road, while the flanges 13 define the surface of the road at the opposite edges. In surfacing the road, it is the practice to run a finishing machine or device on the treads of the rails, thereby imposing more or less weight on the rails, and the base flanges 12 are therefore 90 of sufficient width to support the rails on the ground or road bed. As shown, the base flanges 12 are considerably wider than the tread flanges 13.

In carrying out the present invention, the rail ends are rigidly secured together, and, for this purpose, a longitudinally slidable latch 14 is provided at one end of each rail and is slidable in a U-shaped guide 15. Said guide has feet 16 at its ends extending away 100 from one another and riveted or otherwise secured to the web 11 of the rail near the corresponding end thereof between the flanges 12 and 13. The latch 14 is of U-shaped section, and has the web 17 bearing 105 against the web 11 of the rail and the outwardly projecting flanges 18 bearing against the arms of the guide 15 with the edges of the flanges slidably abutting the intermediate or yoke portion of said guide. The flanges 18 have outwardly extending stop lugs 19 at their inner ends to strike the 110

guide 15 when the latch is projected, and thus limit the projection of the latch. Said flanges 18 are provided at their outer or forward ends with outstanding lugs or portions 20 which contact with the guide, when the latch is retracted, to limit such retraction of the latch.

The other end portion of each rail is provided with a latch socket for the reception 10 of the latch of the companion rail. Thus, a U-shaped socket member 21 has the angularly extending feet 22 at its terminals riveted or otherwise secured to the web 11 of the rail, similar to the guide 15, adjacent 15 to the corresponding end of the rail, and such socket member 21 is of a size to snugly receive the latch of the adjacent rail when the latch is projected by sliding it into the socket. This provides a slip-joint connection 20 between the rails, and when the rails are laid end to end, the latches are readily projected into the sockets of the companion rails, to maintain the rail ends in alinement, and to support the rail ends against depression or relative lateral or vertical displacement.

The socket member 21 is provided in the arms thereof adjacent to the yoke or intermediate portion with apertures 23 for receiving a stake 24, which is preferably of circular cross section as shown. Thus, the stake 24 can be driven down through the member 21, which also forms a stake socket, for anchoring the rail ends in place on the ground. This stake also forms a part of the joint for clamping the rail ends together. Thus, the lugs 20 of the latch have notches 25 to register with the apertures 23 of the latch and stake socket member 21 when the latch is projected into the socket with the lugs 19 contacting with the guide member 15, as seen in Fig. 2. Then, when the stake 24 is driven down through the apertures 23 it engages in the notches 25 and the latch is drawn tightly into place in the member 21, thereby clamping the rail ends together tightly in abutment. As a result, the joint is made perfectly rigid and secure, and is also anchored to the ground by means of the stake. It is preferable to have a set screw 26 in the yoke or intermediate portion of the socket member 21 to bear against the stake and clamp the parts together against accidental loosening or separation. It is therefore apparent that when the rails are laid end to end, the latches can be conveniently projected into the latch sockets, and the stakes 24 then driven down through the members 21 for making the joints rigid 50 and anchoring them to the ground. In taking the rails up, the set screws 26 are loosened and the stakes 24 withdrawn, which permit the latches to be retracted and the rails then removed laterally from place.

65. Each rail also has a stake socket between

the ends thereof including a U-shaped member 27, similar to the member 21, having the feet 28 riveted or otherwise secured to the web 11 of the rail between the flanges 12 and 13. The arms of the member 27 have the apertures 29 for the passage of the stake 31, and a set screw 30 is carried by the member 27 to bind against the stake similar to the set screw 26. This enables the intermediate portion of the rail to be anchored in place on the ground. As shown, the stakes 24 and 31 contact with or bear against the edges of the lower flange 12 of the rails.

Sometimes it is desired or required to use superposed rails, such as shown in Fig. 5, wherein there are upper rails seated on the lower rails for increasing the height of the form. The flanges 12 and 13 of the rails are therefore provided with apertures or bolt holes 32 at suitably spaced points from the ends and intermediate the ends, so that when the rails are seated one on the other, bolts 33 or other fastening means can be inserted through the registering apertures for clamping the upper and lower rails together with the lower flanges 12 of the upper rails secured on the upper flanges 13 of the lower rails. In this arrangement, as seen in Fig. 5, longer stakes 24' and 31' are used, whereby they can be driven down through the respective members 21 and 27 of the upper and lower rails. Such stakes will therefore not only anchor the rails to the ground and make the joints secure, but will also brace the upper rails from the lower ones in addition to the clamping bolts 33. The upper rails as well as the lower ones can be of different heights.

Having thus described the invention, what is claimed as new is:

1. A concrete form comprising rails to be disposed end to end, and members carried by the adjacent ends of said rails adapted to have a slip connection for holding the rails in alinement, one of said members having an opening for receiving a member to lock the parts together.

2. A concrete form comprising rails to be disposed end to end, and members carried by the adjacent end portions of said rails and adapted to have a slip connection for retaining the rails in alinement, said members having portions for receiving a member driven between them and so arranged that said member holds the rail ends together tightly.

3. A concrete form comprising rails to be disposed end to end, a socket member carried by one rail, a member carried by the other rail to enter said socket member and hold the rails in alinement, and means between said members for locking them together with the rails in abutment.

4. A concrete form comprising rails dis-

posed end to end, U-shaped members having their terminals secured to the rails, and a latch to fit in said members having a web adjacent to the rails and longitudinal flanges projecting away from the rails to slidably engage the yoke portion of one of said members.

5. A concrete form comprising rails disposed end to end, a U-shaped guide member having its terminals secured to one rail, a latch slideable in said guide having a web adjacent to the web of said rail and flanges projecting away from said rail and slidably engaging the yoke portion of said member, and a socket member carried by the other rail to receive said latch.

6. A concrete form comprising rails disposed end to end, a U-shaped guide member having its terminals secured to one rail, a latch slideable in said guide having a web adjacent to the web of said rail and flanges projecting away from said rail and slidably engaging the yoke portion of said member, and a socket member carried by the other rail to receive said latch, said flanges having lugs to contact with said guide member for limiting the movement of the latch.

7. A concrete form comprising rails disposed end to end and having portions to fit together with a slip joint for holding the rails in alinement, and means engageable with said portions by movement relatively to the rails for retaining the rails in abutment.

35 8. A concrete form comprising rails disposed end to end and having a slip joint, and a stake cooperable with said joint for retaining the rails in abutment and to enter the ground for anchoring the rails in place.

40 9. A concrete form comprising rails disposed end to end, and means for securing the rails end to end including a stake adapted to be driven into place relatively to the rails to first secure the rails together and then enter the ground.

45 10. A concrete form comprising rails disposed end to end, and means for securing the rails together having portions arranged to receive a stake when the rails have been brought together end to end so that the stake can be driven into the ground by movement relatively to the rails, said portions being so arranged that the stake assists in holding the rails together.

55 11. A concrete form comprising rails to be disposed end to end, a socket member carried by one rail, a member carried by the other rail to enter said socket member, said members having means for receiving a stake driven into the ground.

60 12. A concrete form comprising rails to be disposed end to end, members carried by the rails to fit together with a slip joint and hold the rails in alinement, and a member movable relatively to the rails and en-

gageable with said members for retaining the rails in abutment.

13. A concrete form comprising rails to be disposed end to end, and members carried by the rails to fit together with a slip joint 70 and having portions for the reception of a stake driven into the ground for holding the rails together.

14. A concrete form comprising rails to be disposed end to end and having a slip- 75 joint formed for the reception of a stake to lock the rails in abutment.

15. A concrete form comprising rails to be disposed end to end, a latch carried by one rail, a socket member carried by the 80 other rail for receiving said latch to hold the rails in alinement, said member and latch having portions for the reception of a member to move relatively to the rails and lock said members together with the 85 rails in abutment.

16. A concrete form comprising rails to be disposed end to end, a latch member carried by one rail, and a socket member carried by the other rail to receive said latch 90 and having means for the passage of a stake, said latch being formed for the engagement of said stake to secure said latch and member together.

17. A concrete form comprising rails to 95 be disposed end to end, a socket member carried by one rail, a member carried by the other rail to enter said socket member, the socket member having means for the passage of a stake, the second named member having 100 a portion for the engagement of the stake, and clamping means carried by the socket member to engage the stake.

18. A concrete form comprising rails to be disposed end to end, a socket member 105 carried by one rail, a member carried by the other rail to enter the socket member, the socket member being apertured for the passage of a stake, the second named member 110 having a portion for the engagement of the stake, and a set screw carried by the socket member to engage the stake.

19. A concrete form comprising rails to be disposed end to end, a U-shaped socket member having its terminals secured to one 115 rail, a member carried by the other rail to enter said socket member, the arms of said socket member having apertures for the passage of a stake and the second named member having a portion for the engagement of the stake, and clamping means carried by the yoke portion of said socket member to bear against the stake.

20. A concrete form comprising rails to be disposed end to end, a member carried 120 by one rail for the insertion of a stake, and means carried by the other rail to fit said member and be engaged by the stake for securing the rails in abutment.

21. A concrete form comprising rails to

be disposed end to end, a guide member carried by one rail, a latch slideable in said guide member, and a socket member carried by the other rail to receive said latch and having means for receiving a stake, said latch being formed for the engagement of the stake for securing the rails together.

22. A concrete form comprising rails to be disposed end to end, a guide member carried by one rail, a latch slideable in said guide member along the web of the rail, a socket member carried by the other rail for

receiving said latch, said socket member being apertured for receiving a stake and the latch being notched to be engaged by said stake, the latch having a portion to bear against the guide member when the stake engages the latch for holding the rails together in abutment, and clamping means carried by the socket member to bear against the stake toward the corresponding rail.

In testimony whereof I hereunto affix my signature.

FRANCIS O. HELTZEL.
